SPEAKER AND AMPLIFIER FOR MUSICAL
INSTRUMENTS

Wayne L. Kimbell, 4319 Melrose Ave., Los Angeles,
Calif. 90029, and Richard P. Edlund, 3052 "A"
Sacramento St., San Francisco, Calif. 94155

Filed Mar. 9, 1972, Ser. No. 233,398

Term of patent 14 years

Int. Cl. D14—01

U.S. Cl. D26—14 G

Fig. 1

Fig. 2

Fig. 3

Fig. 4

Fig. 5

FIG. 1 is a perspective view of a speaker and amplifier for musical instruments showing the novel features of the design;

FIG. 2 is an end elevational view thereof as viewed from the right of FIG. 1;

FIG. 3 is a bottom plan view of FIG. 1;

FIG. 4 is a rear elevational view of FIG. 1;

FIG. 5 is an enlarged view of a portion of FIG. 1;

FIG. 6 is a perspective view of another embodiment of the design shown in FIG. 1;

FIG. 7 is an end elevational view thereof as viewed from the right of FIG. 6;

FIG. 8 is a bottom plan view of FIG. 6;

FIG. 9 is a rear elevational view of FIG. 6; and

FIG. 10 is an enlarged view of a portion of FIG. 6.

We claim:

The ornamental design for a speaker and amplifier for musical instruments, as shown.
